Be it known that I, EMIL G. SAUER, a citizen of the United States, and a resident of Brooklyn, in the county of Kings, State of New York, 5 have invented a new and original Design for Carpets and Borders, of which the following is a specification.

This invention comprises two parts—namely, the design A for carpet and the design B for border; and I do hereby declare that the drawing accompanying this specification conveys to any one a clear understanding of the same, and is sufficient to enable such person to use my invention.

15 The design A is characterized by small conventional figures in close arrangement, covering the entire field of the design and constituting its leading feature.

The design B is characterized by small con-

ventional figures in close arrangement with a 20 border of larger conventional figures and constituting its leading feature.

What I claim, and desire to secure by Letters Patent, is—

2. In a design for carpet, the border B, substantially as shown.

3. The design for carpet, comprising the body A and the border B, substantially as 30 shown.
